ELECTRON GUN FOR TRAVELING WAVE TUBE

George R. Brewer, Palos Verdes Estates, Calif., assignor to Hughes Aircraft Company, a corporation of Delaware

Application December 2, 1954, Serial No. 472,581

1 Claim. (Cl. 315—3.5)

This invention relates to electron discharge devices and more particularly to an electron gun for producing an electron stream having a substantially uniform diameter.

In electron stream-type of traveling-wave tubes, an electron stream is projected through a conductive helix to interact with and amplify a traveling wave propagated therealong. A solenoid is generally disposed concentrically about the helix to focus or confine the stream electrons. The stream is said to be focused in Brillouin flow when the cathode from which the stream electrons are emitted is not immersed in the magnetic field developed by the focusing solenoid. The stream is said to be in "confined flow" when the cathode is immersed in a uniform magnetic field. Both of these types of electron flow may be usefully employed. However, Brillouin flow is somewhat more difficult to produce due to the particular type of stream focusing structure employed in developing such flow. Further, in either case original disturbances in the electron stream cause the stream to ripple or to vary in diameter. Traveling-wave axial electric fields decay very rapidly with stream radius. Rippling thus can and does substantially decrease the power and efficiency of a traveling-wave tube by periodically preventing optimum traveling-wave interaction.

It is therefore an object of the invention to provide an electron gun for reducing the diameter variations in a magnetically confined electron stream.

It is another object of the invention to provide an improved electron gun for a traveling-wave tube in which electron flow is magnetically confined.

In accordance with the invention a cylindrical cathode, which may have a substantially flat emission surface, is employed as an electron source. A focusing electrode is positioned about the cathode and maintained at an appropriate potential to develop a converging electron stream. The stream is then directed through an annular disc electrode at such an angle that the rate of change of the stream radius with respect to distance is substantially zero at a point in a subsequent equipotential region. The total axial magnetic flux linking the stream is meanwhile maintained constant in order to preserve a true confined electron flow.

The novel features which are believed to be characteristic of the invention, both as to its organization and method of operation, together with further objects and advantages thereof, will be better understood from the following description considered in connection with the accompanying drawings, in which an embodiment of the invention is illustrated by way of example. It is to be expressly understood, however, that the drawings are for the purpose of illustration and description only and are not intended as a definition of the limits of the invention.

Fig. 1 is a sectional view of a traveling-wave tube with which the electron gun of the present invention may be employed;

Fig. 2 is a graph of a family of curves illustrating the

2

effect of entrance conditions upon the ripples of an electron stream; and

Fig. 3 is a diagrammatic sectional view of a solid electron stream showing the trajectories of the outer electrons which may be produced with the use of the gun of the present invention.

Referring to the drawing, there is illustrated in Fig. 1 a traveling-wave tube 10 having an input matching cavity 12 and output matching cavity 16 with coaxial input 10 and output cables 14 and 18, respectively. An envelope 20, which provides an evacuated chamber of the traveling-wave tube 10, consists of a long cylindrical structure which has an enlarged portion 19 at the left extremity thereof, as illustrated in the drawing.

Within the enlarged portion 19 at the left extremity of the envelope 20, an electron gun 22 is shown comprising a cathode 24 which is provided with a filament 26, a focusing electrode 28 and an accelerating anode 30 having an aperture 31. Focusing electrode 23 has a frusto-conical internal surface disposed at an acute angle from its axis of revolution. A filament source of potential 32 is connected across the filament 26, the positive side of the filament 26 being connected to the cathode 24. Cathode 24 is maintained at ground potential and focusing electrode 28 is maintained at a suitable potential negative with respect to ground by means of a biasing source of potential 34. Electrons emitted from the cathode 24 are accelerated from the cathode by an accelerating source 36 which is connected between ground and accelerating anode 30.

Proceeding along from the gun 22 in the direction of electron flow produced thereby, there are positioned successively about the path of the stream, a matching ferrule 38 connected by a lead 40 to a helix 42 which is, in turn, connected by a lead 44 to a matching ferrule 46. A collector electrode 48 is positioned at the end of the electron stream path so as to intercept or collect the stream electrons.

Helix 42 which serves as a slow-wave circuit for the traveling-wave tube 10 is fabricated from a material such as tungsten so that it retains its form especially with respect to the ratio of its pitch to its diameter. Ferrule 38, lead 40, helix 42, lead 44, and ferrule 46 are all maintained at the same potential by means of an appropriate connection 50 from ferrule 38 to accelerating anode 30. The magnitude of the voltage supplied by accelerating source 36 thus determines the velocity of the stream flowing through the helix 42. This voltage may be of the order of 1000 volts with respect to ground. The collector electrode 48 is maintained at the same potential as accelerating anode 30 by means of a connection to the positive terminal of accelerating source 36.

A solenoid 52 is axially positioned symmetrically about the complete length of the envelope 20. A direct current is maintained in the solenoid 52 by means of a potential source, such as a battery 54, so as to produce an axial magnetic field of uniform density along the length of the tube of the order of 1000 gauss.

In the operation of the amplifier 10 an input signal to be amplified is applied through input coaxial cable 14 to input cavity 12 to launch a traveling-wave along the helix 42. Interaction between the electron stream and this traveling wave results in a transfer of energy from the stream to the wave which causes it to grow or increase in amplitude. At the end of the helix 42 the amplified electromagnetic wave flowing along the lead 44 connecting helix 42 to ferrule 46 excites an electric field in output matching cavity 16 to provide an amplified output signal which is available through output coaxial cable 18.

In order to operate the traveling-wave tube 10 at optimum power and efficiency, it is necessary to project the electron stream developed by the gun 22 as close to the

helix 42 as possible. A rippling in an electron stream as shown by theory and experiment occurs with the use of an axial magnetic field such as that produced by the solenoid 52. This rippling manifests itself as a plurality of stationary periodic diameter variations. In order to maintain the stream in Fig. 1 as near the helix 42 as possible, these variations may be minimized by converging the stream from the cathode 24 to a suitable diameter at a point beyond the anode aperture, the rate of change of the stream radius, r , with respect to distance being zero at that point. The need for such an electron gun to accomplish such a result is illustrated in Fig. 2, where a ratio,

$$\frac{r_{\max}}{r_0}$$

proportional to the maximum stream radius, $r_{\max}$, is plotted as a function of a ratio,

$$\frac{W_H}{w_p}$$

proportional to axial magnetic flux density, B_0 , for different stream entrance angle, θ , where

$$x = \tan \theta = \left[\frac{d\left(\frac{r}{r_0}\right)}{d\left(\frac{z}{a}\right)} \right]_{z=z_0}$$

z_0 is the axial position of the electron gun anode;
 $r_{\max}$ is the maximum stream radius;
 r_0 is the stream entrance radius;
 z is the axial distance from a suitable reference plane;
 θ is the stream entrance angle measured from the line $r=0$;
 x is the tangent of the entrance angle θ ;

$$a = \frac{2u_0}{w_p}$$

u_0 being the electron stream velocity;

$$w_p = \left(\frac{R_0 n}{P_0} \right)^{1/2}$$

R_0 being space charge density, P_0 being the permittivity of free space; and n being the electron charge to mass ratio, e/m ; and

$$w_H = \frac{nB_0}{2}$$

B_0 being the axial magnetic flux density in the stream.

It is evident from Fig. 2 that the condition $x=0$ is the best for reducing the radial stream variations. In order to design the electron gun 22 properly, the trajectories of the outer electrons in the stream must therefore be examined. Referring to Fig. 3, the cathode radius is indicated by r_c . The distance from the cathode 24 to the anode 30 is represented by L . The diameter of the anode aperture 31 is denoted by D . The planes $z=-z_0$ and $z=+z_0$ indicate the planes along the stream where electron motion changes from linear to curvilinear motion and from curvilinear to linear motion, respectively.

In order to determine the correct angle at which to converge the stream, a slope equation is developed in the following approximate analysis. By definition the axial component of stream velocity, u_z , is given in terms of the voltage of anode 30, V_0 , as

$$u_z = (2nV_0)^{1/2}$$

The radial component of velocity, u_r , is the time integral of acceleration or

$$u_r = - \int_{-t_0}^{+t_0} nE_r dt - u_{r1}$$

where

$+t_0$ and $-t_0$ correspond respectively to $+z_0$ and $-z_0$, the extent of the lens field, in time;
 u_{r1} is the absolute value of the radial velocity at $z=-z_0$;
 E_r is the radial electric field intensity.

It can reasonably be assumed that the axial electric field intensity, E_z , on the right side of the anode 30 is substantially zero since the collector 48 is at the same potential as the anode. Space charge can also be neglected in most practical cases. Using E_z as the axial electric field intensity at the anode 30, according to Gauss' law

$$2\pi r_0 \int_{-z_0}^{+z_0} P_0 E_z dz - \pi r_0 P_0 E_z = 0$$

the following being obtained

$$20 \quad \int_{z_0}^{+z_0} E_z dz = \frac{r_0 E_z}{2} \quad (3)$$

Substituting

$$25 \quad dt = \frac{dz}{u_z}$$

in Equation 2

$$30 \quad \frac{u_r}{u_z} = \frac{-n}{u_z^2} \int_{-z_0}^{+z_0} E_z dz - \frac{u_{r1}}{u_z} \quad (4)$$

Substituting Equations 1 and 3 into Equation 4 and noting that $u_r=0$ at $z=+z_0$

$$35 \quad \frac{u_{r1}}{u_z} = \frac{r_0 E_z}{4V_0} = \tan \theta \quad (5)$$

which is the tangent of the angle, θ , of convergence as indicated. According to the diode equation, for space charge limited electron flow, the field intensity at the anode E_{za} is given by

$$40 \quad E_{za} = \frac{4V_0}{3L}$$

therefore from Equation 5

$$45 \quad \tan \theta = \frac{r_0}{3L} \quad (6)$$

The relationship in Equation 6 should therefore be maintained when the stream convergence is substantially linear. This can be accomplished by properly shaping focusing electrode 28 and by maintaining it at an appropriate potential. The exact shape of the focusing electrode can be determined in individual cases with the use of an electrolytic tank by methods well known in the art. Equation 6 is a paraxial ray equation, i. e. where $u_r \ll u_z$, in a thin electrostatic lens, i. e. where $z_0 \ll D$, which is obviously provided with the anode aperture 31. z_0 should obviously be smaller than L .

In order to maintain the confined flow condition the total flux linking the stream should be maintained constant. If the stream converges substantially linearly, then

$$50 \quad \frac{B_c}{B_0} = \left[\frac{r_0}{r_c} \right]^2$$

is a good approximation for $r_0 \ll L$ where B_c and B_0 are the magnetic flux densities at the cathode and at the anode, respectively. According to the geometry of the stream

$$65 \quad r_c = r_0 - L \times \frac{r_0}{3L}$$

therefore

$$70 \quad \frac{r_0}{r_c} = \frac{3}{4} \quad (7)$$

or

$$75 \quad \frac{B_c}{B_0} = \frac{9}{16} \quad (8)$$

In using Equation 8 the flux density should then be increased linearly from the cathode to $z=z_0$.

The invention is still practicable even if r_0 is not small in comparison to L . Equation 8 will then not be quite the correct ratio, but must be changed accordingly. The ratio given by Equation 7 should be changed likewise.

What is claimed is:

In a traveling-wave tube having an electron gun for producing an electron stream having a substantially uniform diameter, said electron gun comprising a cylindrical thermionic cathode, a focusing electrode having a frustoconical internal surface of revolution disposed concentrically about said cathode and having a shape to develop a substantially linearly converging electron stream from said cathode, an apertured disc electrode disposed coaxially with said cathode and spaced axially therefrom, the distance between said cathode and said disc electrode being equal to L , means for maintaining said disc electrode at a potential to accelerate the electrons emitted at said cathode through the aperture of said disc electrode, means for maintaining said focusing electrode at a potential to cause said stream to converge to a predetermined radius, r_0 , at a plane where the rate of change of the radius of said stream with respect to the distance along

5 said stream equals zero after the stream emerges from the anode aperture, said stream being converged substantially linearly at an angle given approximately by

$$\theta \approx \frac{r_0}{3L}$$

10 and means for maintaining an axial magnetic field within said stream, said field having a linear variation from said cathode to said disc electrode given by the following relationship:

$$\frac{B_c}{B_0} \approx \frac{9}{16}$$

15 where B_c is the axial magnetic flux density at said cathode, and B_0 is the axial magnetic flux density at the plane intersecting said stream where said stream reaches the radius, r_0 , r_0 being substantially smaller than L .
